UNITED STATES PATENT OFFICE

ISAAC W. LITCHFIELD, OF BOSTON, MASSACHUSETTS, ASSIGNOR TO BEMIS INDUSTRIES, INCORPORATED, OF BOSTON, MASSACHUSETTS, A CORPORATION OF DELAWARE

CASEMENT LOCKING MECHANISM

Application filed November 21, 1930. Serial No. 497,187.

This invention relates to an improved regulating and locking means for a swinging closure and is particularly adapted to operate and positively to lock a swinging casement or French window. The present invention particularly relates to a regulator of the type having a swinging lever connected to the window sill or ledge and having a sliding engagement with a guiding means upon the swinging window sash.

More particularly the present invention provides a simple inexpensive and effective regulator of this type which not only is adapted to lock the window sash in a plurality of open positions by a simple movement of the regulator handle which is connected to the lever but also is adapted positively to lock the window in its closed position, thus preventing leakage of cold air into the interior of the building and substantially sealing the window against objectionable moisture penetration.

Preferably this novel locking means is associated with the swinging lever and its control handle is arranged so that one movement of the lever is effective in releasing the window from one of its opened positions while another simple movement of the lever is effective in causing the positive locking of the window in its closed position. To permit this desirable result I preferably arrange the lever so that it has a substantially longitudinal or endwise movement in relation to its pivotal connection to the window sill. Accordingly the lever handle can be actuated to cause the endwise movement of the lever when such a movement is permitted by the guiding and locking means associated with the outer end of the lever and with the window, this means being arranged to permit such a longitudinal movement of the lever when the window is substantially in its closed position. Under these conditions I preferably provide locking means to engage a part carried by the lever when it is longitudinally moved positively to lock the same against swinging movement and accordingly to lock the window in its closed position.

Preferably the locking means is provided

with a tapered or inclined surface to provide a wedge or cam-like effect which may be effective in causing the bringing of the swinging closure, casement or window sash into firm engagement with the outer face of the abutting frame.

The latching means for holding the window in desired open position is preferably provided with a locking block, which presents a wedging action in latching position to hold the window securely and positively, but to allow release readily when the position of the window is to be changed; the wedging action preventing rattling or swinging of the window. The particular construction is further arranged to be shielded so that ice or rain will not affect the operation of the device.

The handle for operating the device may be so constructed as to permit operation from within an inside screen, whereby the screen may remain always in position, the device being constructed to allow a tight fit for the screen, so that there are no openings or slots where flies or the like may enter. The device is further constructed to have no detachable parts which might be misplaced, and thereby prevent further operation of the device. The mechanism consists of a few parts, all of which are connected together, providing a simple, easily operated, and easily attached structure.

Fig. 12 is a view corresponding to Fig. 2 showing a modification of my invention; and

15 Fig. 13 is a section along the line 13—13 of Fig. 12.

The device of my invention is shown in Fig. 1 as attached to a pair of casement or swinging windows, that is the type of window which is hingedly mounted along one vertical edge and swings outwardly to open.

20 The lever 1 which operates the retaining structure for holding the casement 2 in adjusted position as well as being the operative element for locking the window closed, is pivotally mounted on the window sill or frame 3 by a base plate 4 having a pivot 5 (Fig. 3) attached thereto. The opposite end of the lever slidably engages the casement 25 or sash 2 by means of a block or slider 6 (Fig. 6) which is pivotally mounted on the upper side of the lever and moves longitudinally along a slide and retaining member or stop bar 7, which is attached horizontally 30 along the base portion of the casement or sash 2, the block presenting a surface of considerable area to take the thrust from the lever as the window is swung on its hinges.

35 The construction is such that a rocking movement of the lever in a vertical plane, and then a swinging movement in a horizontal plane is necessary to open and close the window, and a sliding movement longitudinally of the lever is necessary to lock the window in closed position, the connection at 40 the base plate being constructed to permit these movements. The base plate 4 is mounted upon the sill or frame by a group of screws 9 extending through projecting portions 10 of the plate. The center of the plate has a projecting boss 11 (Fig. 9) which acts as a fulcrum for the rocking of the lever. The center of the boss is provided with a threaded hole into which the pivot pin 5 is inserted, this pin having a surface which 45 engages with a cover plate 12 for the pivotal connection and holds said plate in position as shown in Fig. 9. The cover plate for concealing the pivotal construction is substantially inverted cup-shape, and pivots around the pin 5, cut away portions 13 on each side of the plate permitting the lever 1 to extend therethrough, the cut out portions being of a size to permit rocking movement of the 50 lever. The lever is provided with a longi-

tudinal slot 14, which engages the pivot pin 5, permitting swinging movement of the lever, as well as longitudinal movement thereof. When this construction is used with a screen, the pivotal structure is mounted on 70 the sill or ledge in the plane of the screen. This permits the frame of the screen to engage tightly about the cover plate in order that no open spaces will be left where flies may enter.

75 The slide or stop bar 7 and block or slider 6 construction is arranged to hold the window in open position, and also to permit longitudinal sliding movement of the lever in locking the window in closed position. The slide (Figs. 6, 7 and 8) is constructed to have a rectangular cross-section, one side 16 of which is secured to the casement, and a second side 17 at the lower edge of the side 16 and at right angles thereto is provided with a plurality of evenly spaced notches 18, the spaces between the notches being in effect lugs, engageable with spaced wedge-shaped projecting portions 19 on the block 6. It will be apparent in Fig. 8 in the dot-dash lines that the notches 18 are of a somewhat different spacing than the projections 19, providing a more rigid connection between the block and slide due to the wedging action of the projections. 80 In this construction the notches may be somewhat larger than the projections, to permit more ready reception of the projections, but retaining a construction which will prevent rattling of swinging of the window in retaining position. A third side 20 of the slide extends parallel to the side 16, and is held in position by a fourth side 21 connecting the upper edges of sides 16 and 20. The side 20 acts as a backing for the block 6 85 as in Figs. 6 and 7, to hold the projections 19 in engagement with the notches 18, and also as a shield to prevent ice and snow from getting onto the block to prevent its operation. A spring 22 which rests in a 90 hole in the block 6 presses outwardly on a pin 23, engaging the surface of the side 21 of the slide, this construction acting to hold the notches in engagement with the projections but permitting their disengagement 95 to adjust the window. The block 6 is cut away at 24 adjacent the side 20, so that any ice forming on the lower edge of the side 20 will not freeze to the block 6 to prevent its movement in the slide, the portion 24 being cut back enough so that the block is free from the edge of the side 20 in all positions. When rocking movement is imparted to the lever, the block 6 is forced upwardly, the notches are disengaged and the block 100 may be moved to another position of adjustment. 105

110 I provide in the slide a structure which permits endwise movement of the lever, when the window is in closed position to 115

permit locking the window. As shown in Fig. 8, a pair of elongated notches 25 of a length equal to the slot 14 in the lever, are provided in place of the notches 18, to 5 permit longitudinal movement of the block 6 to a limited extent. One of the notches 25 engages each of the projections 19 so that sliding movement of the block, and accordingly longitudinal movement of the lever is 10 obtained, when the block is in normal retaining position. These notches 25 are located at that end of the slide 7 where the block is normally located when the window is in closed position.

15 In order to prevent longitudinal movement of the lever 1 when not desired, I provide a projection or pin 27 on the under side of the lever, which engages with a slot 28 of the base plate (Fig. 3). This slot is 20 constructed as an arcuate slot, the center of curvature being the pivot pin 5, and having at one end thereof a radial slot, the projecting pin 27 engaging at all times with this slot. The pin as shown in Fig. 3 will 25 be in the radial slot when the window is locked. Longitudinal movement of the lever will move the pin into the arcuate slot, and permit swinging movement of the lever to open or close the window. It will be 30 obvious that while the pin is in the radial slot there can be no swinging movement of the lever and accordingly the window is held securely closed. The arcuate slot prevents 35 longitudinal movement of the lever except when the window is in closed position, accordingly there can be no swinging or rattling of the casement due to the lever sliding along the pivot.

40 A locking means is further provided for holding the window closed, as most clearly shown in Figs. 2, 4 and 5. A plate 30 is attached to the sill or frame by any desired means and supports a parallel plate 31 in spaced relation thereto, a connecting portion 32 holding the plates in spaced position. A projecting portion or pin 33 on the underside of the lever is engageable with the edge of the plate 31 when the lever is moved longitudinally. As shown in Fig. 2 the 45 plate is arranged so that the pin engages the plate in locking position, but upon movement of the lever to unlocked position for opening the window, the pin is moved beyond the edge of the plate and permits 50 swinging movement of the lever. The edge of the plate 31 is preferably arranged at an angle to the casement, to give a wedging action to the locking means, drawing the casement tightly closed.

55 As shown in Fig. 11, I provide a folding handle for the lever, to permit it to be folded out of the way comprising an extension 35 integral with the lever extending beyond the pivotal connection and a handle portion 36, which is pivotally attached to

this extension as at 37, the surface of the attaching portion of the handle which engages the surface of the extension being provided with a projecting pin 38 which is engageable with a notch 39 in the end of 70 the extension when the handle is in operative position. A second projection 40 is provided on the handle 36 engaging in a notch 41 on the side of the extension, the projection 40 being provided with a head 75 42 which engages the under side of the extension. A longitudinal slot 43 is provided in the extension at the pivotal connection, a spring 44 acting to retain the pivot at one end of the slot, so that the pins 38 and 40 80 engage their respective notches. To fold the handle, it is pulled outwardly, the pin 38 is drawn out of the notch 39 and the handle can pivot about the point 37, the end of the extension being preferably 85 rounded to permit free sliding movement of the pin 38 along the end except in locking position.

90 Referring to the embodiment of the invention shown in Figs. 12 and 13, in which I show a more simple structure which is particularly advantageous where screens are not used, as in office buildings, a lever 50 similar to the lever 1 is pivoted at 51 to the frame and slidably engages the casement at 52, the slide and retaining structure previously described being the same in this modification. The locking feature 53 may be similar in all respects to the locking mechanism of Figs. 4 and 5 above described. 95 I have provided a more simple pivotal connection in this embodiment, this connection comprising a base member 54 attached to the sill or frame, a pivot support 55 in parallel spaced relation thereto, and connected thereto by a connecting portion 56. The pivot support carries thereon a headed pivot pin 57 engaging with a longitudinal slot 58 in the lever. A pin 59 extends downwardly from the lever and engages a notch 60 in the plate 55, when the lever is in locked position as in Fig. 12. When the lever is moved longitudinally to unlock it, the pin 65 disengages the notch and moves along the circular edge 61 of the plate, the edge 61 100 acting to hold the pivot pin 57 at the end of the slot and prevent undesired endwise movement of the lever along the pivot during opening and closing of the window and also while the window is open, which permits the window to be held securely and 105 also prevents rattling and undesirable swinging of the window. The head of the pivot pin is held resiliently against the surface of the lever by a lock washer 62, which 110 prevents rattling while permitting desired rocking movement of the lever. I also provide a handle or finger lift 63 attached between the pivotal connection and the slide construction, thus avoiding any ex- 115 120 125 130

tension beyond the pivotal connection. This device is suitable where a screen will not interfere with operation of the handle. In this modification, as in the preceding, several of the parts are reversible as, for example, the sliding block, and the locking member. The pivotal construction and handle of this modification are also reversible. This permits attachment to windows opening to the right or to the left.

The operation of the device is as follows assuming the mechanism to be properly connected to the frame and casement and the window to be locked in closed position, that is, in the position shown in full lines in Fig. 2. The lever 1 is moved longitudinally thereof in a direction toward the block 6, that is, in a direction to unlock the projecting portion 27 from the radial slot 28 and the pin 33 from the plate 31, the slots 25 permitting the block end of the lever to slide, and the slot 14 permitting the pivot point to slide longitudinally. The handle portion is now depressed, to rock the lever about the fulcrum 11, raising the outer end of the lever and the block to disengage the notches 25 and projections 19. The lever is then swung horizontally and the window opens outwardly, the block 30 sliding in the slide 7. When it is opened the desired amount, the lever is released and the projections 19 engage any set of notches 18 to retain the window in position. Since the pin 27 engages the circular slot, the lever is held against longitudinal movement and no swinging of the window may occur. When the window is to be closed, the handle is again depressed and swung horizontally until the window is closed. The lever is 40 then moved longitudinally in a direction opposite to its first motion and to bring the projections 27 and 33 into locking position, the notches 25 in the slide and the slot 14 in the lever also permitting this longitudinal movement. The handle is folded when the window is in any desired position by pulling longitudinally thereof and turning the handle about its pivot.

The embodiment shown in Figs. 12 and 13 operates in a similar manner the finger lift or handle 63 being raised, after having moved the lever longitudinally, thus imparting the same movement to the block as in the preceding modification. The opening and closing of the window is accordingly accomplished by a swinging of the lever, the retaining means acting as above, and locking of the window results from similar longitudinal movement of the lever.

The structure of the first modification is preferably made of brass or similar ornamental metal, and is generally used in residences and the like where appearance is an important factor and where screens are generally employed, since this modification per-

mits operation without moving the screen. The modification of Figs. 12 and 13 is suitable for office buildings, factories, warehouses and the like, where a satisfactory operative device is desired, but where screens are not generally used.

It will be readily apparent that the number of notches and projections may vary. A single projection of the block would operate with the remainder of the mechanism although a pair of projecting portions provides best wedging action, the number of elongated notches 25 being at least as great as the number of projections.

Accordingly I have constructed a locking and retaining mechanism for a casement window which consists of a lever pivotally connected to the frame adjacent one end and slidably engaging a member mounted on the sash to permit opening and closing of the window. The sash member is provided with lugs or notches with which a portion of the lever, that is, the projections on the block, is selectively engageable to retain the window in adjusted position, the projections being disengageable by upward movement of the end of the lever on which they are mounted and being engageable by downward movement, the latter motion being made more positive by spring means engaging a portion of the slide to assure engagement with the lugs or notches. The lever is provided with a locking means which comprises a locking plate on the frame which is engageable with a portion of the lever to prevent movement of the lever when the window is closed. This locking is accomplished by a slot in the lever at the pivot point, and by certain of the notches being lengthened or the lugs cut away on the sash, to permit the lever to move longitudinally of itself to engage the locking position on the lever with the frame member. An additional notch is provided adjacent the pivot, into which a projecting portion of the lever extends in locking position, and is locked or unlocked by the same motion as the preceding locking means, that is, the longitudinal lever movement. A cam member, the circular slot or edge of the pivot member, prevents longitudinal movement of the lever except when the window is closed, the end of the cam having a locking notch or slot to lock the window closed.

I also provide a folding handle construction, if desired, which is mounted on an extension of the lever beyond the pivot.

It should be understood that the present disclosure is for the purpose of illustration only and that this invention includes all modifications and equivalents which fall within the scope of the appended claims.

I claim:

1. A device for retaining a window frame member and a sash member therefor in po-

- sition, which comprises a lever slidably engageable with one member and pivotally engageable with the other, a slot in said lever at its pivotal engagement to permit limited 5 longitudinal movement thereof, means to prevent said longitudinal movement except when said sash is in closed position, and means to lock said sash in closed position operable by said longitudinal movement of 10 the lever, said locking means comprising a locking element adapted to be mounted on one of the members and engageable with a portion of the lever.
2. A device for retaining a window frame member and a sash member therefor in position, which comprises a lever adapted to engage slidably with one member and pivotally to engage the other, a slot in said lever at said pivotal connection to permit limited 15 longitudinal movement thereof, means to prevent said longitudinal movement except when said sash is in closed position, and means to lock said sash in closed position operable by said longitudinal movement of 20 the lever, said locking means being engageable with a portion of the lever and a folding handle extending beyond the pivotal connection, for operating the lever.
3. Closure locking and operating mechanism comprising a lever, a pivotal mounting with which the lever has a pivotal connection, a slider articulated to the end of the lever, a slide in interfitting relation with the slider, a plurality of cooperating protuberances and recesses provided by the slider and slide, resilient means disposed between a portion of the slide and slider, the pivotal mounting providing a fulcrum for the lever so that the latter may be rocked to stress 30 the resilient means and permit disengagement of the protuberances and recesses whereby the lever may be swung about its connection to the mounting to move the slide in relation to the slider, the resilient means tending automatically to return the protuberances and recesses into interfitting relation when the pressure tending to rock the lever about its fulcrum is released, the pivotal mounting of the lever being arranged 40 to permit longitudinal movement of the lever in one radial direction in relation to its pivotal connection, and means cooperating with a part of the lever and engageable with said part upon longitudinal movement 45 of the lever to hold the lever and the slider in locked position.
4. The combination of a closure operating and locking mechanism with a swinging closure and a fixed frame member to which 50 the closure is pivotally connected, comprising a pivotal mounting upon the frame member, a lever having a pivotal connection with said mounting, a slide upon the closure, a slider articulated to the end of the lever and 55 engaging said slide, fulcrum means associated with said pivotal mounting to permit the rocking of the lever, interfitting locking means provided by the slide and slider, said locking means being engageable and disengageable in response to rocking movement 60 of the lever, resilient means normally effective to retain the locking means in its locked condition, said lever having a connection with the pivotal mounting that allows longitudinal movement of the lever in one radial 65 direction in relation to its pivotal connection, and a locking element carried upon the frame and engageable with a part of the lever upon longitudinal movement thereof to retain the closure in a closed position.
5. The combination of a window frame, a swinging window, and operating and locking mechanism for the window, said mechanism comprising a lever, a pivotal mounting 70 having a pivot pin about which the lever swings, the lever being slotted to permit its longitudinal movement in relation to said pin, the pivotal mounting providing an arcuate guide with a radial extension, the lever having a part engageable with said guide whereby the lever is restrained from longitudinal movement in relation to its pivot pin except when said part engages the radial extension, a slider articulated to the 75 end of the lever, a slide secured to the window and engaging the slider, and a part upon the window frame engageable by the lever upon longitudinal movement thereof to hold the lever in locked position, whereby the window may be firmly held in its closed position.
6. The combination of a window frame, a window pivotally mounted on the frame, and operating and locking mechanism associated with the window and frame, said mechanism comprising a lever, a pivotal mounting, the lever having an articulated connection with the mounting permitting the swinging of the lever about a fixed axis 80 and permitting its longitudinal movement when in one position in relation to said axis, said pivotal mounting and lever being arranged to provide fulcrum means to permit the rocking of the lever, a slider articulated to the end of the lever, a slide receiving the slider, locking means provided by the slide and slider and arranged to retain the slide in fixed position in relation to the slider, said locking means being releasable upon the rocking of the lever about the fulcrum means, and a locking element engageable with a part of the lever between the slider and the pivotal mounting, said element being secured to the window frame and engageable with said part of the lever upon longitudinal movement of the lever, whereby the lever may be rocked to disengage the locking means and permit movement of the window by the swinging of the lever.

about its pivotal connection and whereby the window may be retained in a firmly locked position by engagement of the locking element with said lever part.

- 5 7. The combination of a window frame, a window hingedly mounted on the frame, and operating and locking mechanism associated with the window and frame, said mechanism comprising a lever, a pivotal
10 mounting, the lever having an articulated connection with the mounting permitting the swinging of the lever about a fixed axis and permitting its longitudinal movement in relation to said axis, said pivotal mount-
15 ing and lever being arranged to provide ful-
crum means also to permit the rocking of the lever, a slider articulated to the end of the lever, a slide receiving the slider, locking means provided by the slide and slider and
20 arranged to retain the slide in fixed position in relation to the slider, said locking means being releasable upon the rocking of the lever about the fulcrum means, a locking element engageable with a part associated with the
25 lever, slider and the pivotal mounting, said element being engageable with said part upon longitudinal movement of the lever, whereby the lever may be rocked to disen-
30 gage the locking means and permit swing-
35 ing movement of the window by a swinging of the lever about its pivotal connection and whereby the window may be retained in a firmly locked position by engagement of the locking element with said part.

35 Signed by me at Boston, Massachusetts,
this nineteenth day of November, 1930.

ISAAC W. LITCHFIELD.
